Primary Examiner — Jonathan J Han*Assistant Examiner* — Caitlin MacKenzie Williams(74) *Attorney, Agent, or Firm* — Ware, Fressola, Maguire & Barber LLP(57) **CLAIM**

The ornamental design for a high heel shoe, as shown and described.

DESCRIPTION

FIG. 1 is a top, left perspective view of a high heel shoe showing our new design;

FIG. 2 is a bottom, left perspective view thereof;

FIG. 3 is a left side elevational view thereof;

FIG. 4 is a right side elevational view thereof;

FIG. 5 is a bottom plan view thereof;

FIG. 6 is an enlarged view of the encircled portion identified as 6 in FIG. 3; and,

FIG. 7 is an enlarged view of the encircled portion identified as 7 in FIG. 4.

The dash-dash broken lines shown in the drawings depict portions of the high heel shoe and form no part of the claimed design. The dot-dash broken lines in the drawings are used to identify areas of enlargement and form no part of the claimed design.

1 Claim, 7 Drawing Sheets(56)
